UNITED STATES PATENT OFFICE.

Grant and Registration of Patents
and to one DANIEL C. REYNOLDS, OF PHILADELPHIA, PENNSYLVANIA.

PROCESS FOR OBTAINING BARK EXTRACTS.

1,220,557.

Specification of Letters Patent. Patented Mar. 27, 1917.

Application filed June 22, 1916. Serial No. 105,311.

To all whom it may concern:

Be it known that I, DANIEL C. REYNOLDS, a citizen of the United States, residing at Philadelphia, in the county of Philadelphia 5 and State of Pennsylvania, have invented certain new and useful Improvements in Processes for Obtaining Bark Extracts, of which the following is a specification.

In the preparation of various compounds, 10 among them being those employed, when added to the water injected into steam boilers, to counteract and nullify the deteriorating effect of the action of the chemicals within the water upon the interior of said 15 boilers, it has long been the custom to steep the barks of certain trees for the purpose of obtaining desired extracts therefrom.

Every known means has been employed to 20 increase the quantity of the extracts or juices from a given amount of a given bark, as it is well known that even with the best of care and pains much of the existing juice is lost with the disposal of the refuse bark, and this occurs even when the latter has been 25 previously cut or macerated into small particles and is both wasteful and costly.

Furthermore, when a batch of bark is boiled in water and the extract obtained therefrom has attained a certain specific 30 gravity, of say seven or eight Baumé, it has been difficult to increase the latter, without decreasing the volume proportionately by evaporation. And furthermore, the apparatus heretofore employed in obtaining the 35 said extracts has not possessed the greatest possible efficiency and has been exceedingly wasteful and expensive to operate.

The object of the invention, therefore, has been to provide an apparatus, which obtains 40 the greatest possible quantity of extract from a given amount of bark; which consumes the least possible amount of steam; which can be cleaned with the most convenience; which permits the liquid carrying 45 the extract from a given batch of bark to be raised in specific gravity by reboiling with a second batch of said bark with the least difficulty and waste energy; and which in every way increases the efficiency of the process.

50 And a still further object is to provide a process and apparatus for carrying out the same, whereby the formerly wasted bark is made into a suitable basis for a sweeping compound for both concrete floors and domestic purposes.

In the carrying out of this process, it is well understood that a different form of the apparatus may be employed from that shown, but as hereinafter described it has given the best results thus far, and is therefore preferred. The drawings show in Figure 1 a perspective view of the whole system; Fig. 2 is a vertical diametrical section of one of the set of extracting tanks; Fig. 3 is a vertical section of the evaporating 60 tank; Fig. 4 is a horizontal section on the line 4—4 of Fig. 3; Fig. 5 is a section on the line 5—5 of Fig. 3; and Fig. 6 is an enlarged detail view of one of the supports used in the tanks for positioning the tubes. 65

Referring to Fig. 1 of the drawings, the preferred arrangement of the apparatus employed in carrying out the present invention is shown as comprising four extracting tanks A¹, A², A³, and A⁴, provided with 70 drain pipes 1, having regulating valves 2, and leading from the bottoms thereof to a common pipe 3, which drops to a lower level and thence through branches 4, controlled by valves 5, into storage tanks B¹, B², and B³. 75

From the lowermost portions of said last-named tanks liquids are led through pipes 8, provided with valves 9, and thence through a common pipe 10 to a centrifugal pump 11, driven by any suitable power (not shown), 80 while from said pump they pass through a pipe 12 upwardly and by branches 13, provided with valves 14, to the upper portions of said first-named tanks. 85

For the purpose of heating the contents 90 of the extracting tanks, and one of the storage tanks, the same are provided with steam coils 18 adjacent to their bottom walls and of any suitable construction, but preferably of the arrangement shown in Fig. 2, each of 95 said coils communicating at one end through suitable reducing valves 19 with a steam supply line 20, leading from any desired source (not shown). At their opposite ends said coils communicate through individual 100 traps 21 and a common pipe 21' with a vacuum line 22, leading to a vacuum-producing device (also not shown).

From one point of the steam supply line, 105 an extension 23 leads to another coil 24 in the bottom of an evaporating tank 25, said extension being provided with a valve 26, which however is not necessarily of the reducing type; the other end of said coil opening through a trap 27 and a pipe 27' into a 110

condensation well, whence this pure water with its latent heat units is reheated and re-injected into the boiler forming the source of steam supply. Said evaporating tank is 5 adapted to be filled through a pipe 30 into which lead branch pipes 31, provided with individual valves 32, from the bottoms of each of the said storage tanks.

The storage tanks are simply cylinders, 10 either with or without covers, but without any special interior construction, except in the case of the one which, as above described, is provided with a steam coil for maintaining the contents of said tank heated until they 15 are drawn off. However, in the extracting tanks the construction is similar to that shown in Fig. 2, and herein lies one of the principal advantages of the system and process, as compared with those known to be 20 at present in operation.

A tank 35 is provided at a relatively short distance from its bottom wall with a substantially horizontally extending partition 36, having an aperture 37, while depending 25 from the sides of the latter is a relatively short section of tube or pipe 38, which extends into, and to a point adjacent to the bottom of, a cup 39, forming with said tube a trap, for the purpose hereinafter described. 30 Extending through said partition and upwardly to a point but a short distance below the plane of the upper terminus of the sides of the tank is a series of substantially parallel tubes 41, open at both ends and 35 supported in spaced relation with the sides of the said walls by brackets 42, to which the said tubes are secured by straps 43. Spanning the opening 37 in the partition 36 is a suitable strainer 44, which keeps 40 solid particles from entering and clogging said trap.

In the operation of the device as thus far described, one or more of the extracting tanks is substantially filled with very finely 45 divided bark to a point a short distance below the top of the former, while water is poured upon the same until the said bark is covered, the water being preferably supplied in the nature of a spray acting to settle the dust of the bark, while the process 50 of filling the tank is proceeding.

Steam, preferably at about sixty pounds pressure, is then turned into the coil in the bottom of the tank and the water heated 55 until it boils hard, this action being maintained for approximately twenty-four hours, and during this time the formation of steam adjacent to the coil and below the partition, being unable to pass through the latter past 60 the trap, forces the water in the tubes 41 upwardly in a practically constant stream, whence it sprays over the bark, upon being turned downwardly by deflectors 46, and percolates through the mass. Gradually in 65 this manner the juices of the bark are ex-

tracted, and the water containing the same is run off by gravity into any one of the storage tanks.

If the extract thus formed is not sufficiently dense to come up to the required 70 Baumé, the same is run into the storage tank having the heating coil, from whence it is taken and by the centrifugal pump forced upwardly into the original, or another, of the extracting tanks upon a fresh charge of 75 bark. The same process of boiling and percolating is then continued, after which, if the desired specific gravity has been attained, the extract is run off into a storage tank, and then, if desired, into the evaporating tank. 80

The evaporating tank 25 comprises a cylinder 50, having adjacent to its bottom wall the coil 24 hereinbefore referred to, and near its upper portion a substantially horizontal partition 51, provided with an aperture 52, partially closed by a strainer 53, and having a short tube 54 depending therefrom and into a cup 54', to form a trap, similar to the one previously described, but 85 larger in proportion for the purpose of accommodating the liquid which before being drawn from the tank is heavy and sluggish like molasses.

The upper part of this tank terminates in 90 a large, flaring, funnel-shaped section 55, and a series of parallel tubes 56, extending from below and through said partition, terminate near the upper part of said section, while they are held in spaced position from 95 the walls thereof by brackets 57, similar to those hereinbefore described. The relatively light liquid extract which enters this evaporating tank, is heated by the steam coil 24, and is forced by the steam upwardly 100 through the said tubes and into the air, where little by little it loses its moisture and in falling is led back to the tank by the sides of the section 55, and thence through the partition by way of the trap described. 105

Having thus described my invention, what I claim and desire to protect by Letters Patent of the United States is:—

1. The process which consists in boiling water with bark, to extract certain of the 115 ingredients therefrom, raising the temperature of said liquor to facilitate evaporation, spraying the same through air, to evaporate from said liquor a portion of the moisture therein, and then collecting the resultant 120 liquid.

2. The process which consists in boiling water with bark to extract certain of the ingredients therefrom, removing the liquid 125 thus formed from the spent bark, boiling the said liquid with a lot of fresh bark to raise the specific gravity of the former, then raising the temperature of the liquor to facilitate evaporation and spraying the same through relatively dry air, to evaporate from 130

said liquid a portion of the moisture therein, and then collecting the resultant liquid.

3. The process which consists in boiling water with bark to extract certain of the ingredients therefrom, removing the liquid thus formed from the spent bark, boiling the said liquid with a lot of fresh bark to raise the specific gravity of the former, spraying said liquid through relatively dry

air to evaporate from said liquid a portion ¹⁰ of the moisture therein, and then collecting the resultant liquid.

In testimony whereof I have affixed my signature in presence of a witness.

DANIEL C. REYNOLDS.

Witness:

J. STUART FREEMAN.
